UNITED STATES PATENT OFFICE

2,587,724

PRECAST REINFORCED CONCRETE UNIT

Albert Henderson, Pittsburgh, Pa., assignor, by
mesne assignments, to Peoples First National
Bank & Trust Company, Pittsburgh, Pa., a na-
tional banking association

Original application September 10, 1945, Serial
No. 615,265. Divided and this application De-
cember 11, 1946, Serial No. 715,514

2 Claims. (Cl. 72—61)

1

This invention relates to a building construction utilizing precast reinforced concrete units and, in particular, to a novel unit adapted for use in the construction of buildings.

This is a division from my copending application Serial No. 615,265 filed September 10, 1945, now Patent No. 2,413,562, for precast concrete members.

The extensive use of precast concrete units in building construction has been prevented by the lack of satisfactory means for securing the members together by connections of sufficient strength and rigidity. I have invented a novel form of precast building unit of reinforced concrete characterized by simple and effective provisions for easily and firmly uniting adjacent members. In a preferred embodiment, I embed pipe lengths in the ends of a precast reinforced concrete member adapted to receive tie means projecting from an adjacent member. The pipe lengths have anchor bars welded thereto which are also embedded in the concrete of the members. These bars lap the usual reinforcing bars so that a load applied to one member in a structure is transmitted through the connection to the pipe length and anchor bars in an adjacent member and, by virtue of thelapping of the anchor bars with the reinforcing bars, the load is eventually transferred to the latter by the bond between the concrete and the bars embedded therein.

A complete understanding of the invention may be obtained from the following detailed description and explanation referring to the accompanying drawings illustrating a preferred embodiment. In the drawings,

Figure 1 is a vertical section through the adjacent ends of a pair of aligned girders, the column on which they rest and the footer on which the column stands;

Figure 2 is a partial section taken along the plane of line II—II of Figure 1.

Referring in detail to the drawings, a field-cast footer 10 has anchor bolts 11 embedded therein and projecting upwardly thereabove. A precast column 12 including a shaft 13 and an integral base 14 rests on the footer 10. A layer of grout 15 is preferably spread on the footer before the column is placed thereon.

The column base 14 is larger than the shaft and has pipe lengths 16 embedded therein adapted to accommodate the anchor bolts 11. Stirrups or cross ties 17 extend around the pipe lengths and are welded thereto. The column is secured to the footer by nuts turned on the threaded upper ends of the bolts 11. These nuts are pref-

erably provided with concrete protective covers 18.

The column 12 has longitudinal reinforcing bars 19 embedded therein. Stirrups or cross ties 20 extend around the bars 19 and are welded thereto. The upper ends of the bars project above the top of the column. The projecting ends of the bars constitute ties 21.

Girders 22 and 23 disposed in alignment end-to-end, rest on the column 12. The girders are 10 similar, each having lower and upper reinforcing bars 24 and 25 embedded therein with stirrups or cross ties 26 extending around the bars and welded thereto. As shown in Figure 2, there are three of the bars 24 and two of the bars 25 15 in each girder. Pipe lengths 27 are embedded in the girders adjacent their ends to form holes for receiving the ties 21. The pipe lengths extend between adjacent bars 24. Short anchor bars 28 are welded to the pipe lengths and are 20 embedded in the concrete of the girders between the bars 24 and 25. The anchor bars 28 lap the main reinforcing bars 24 and 25 so that any stress applied to the anchor bars is transmitted to the reinforcing bars through the bond thereof with 25 the concrete.

The abutting ends of the girders 22 and 23 are 30 beveled adjacent the top forming a notch or recess 29. The upper bars 25 have their ends flush with the ends of the girders and are thus exposed in the notch 29 so they can be welded as indicated at 30, thus tying the girders firmly together.

The lower reinforcing bars 24 as well as the upper bars 25 extend beyond the pipe lengths, 35 thus reinforcing the concrete at the extreme ends of the girders. This is possible because the reinforcing bars are located at one side of or between the pipe lengths and not in alignment therewith.

When the girders and column have been assembled, as shown in the drawings, the space between the ties 21 and the pipe lengths into which they extend is preferably filled with grout. When this has been done, a firm rigid connection 45 is established between the reinforcing bars 19 of the column 12 and the reinforcing bars 24 and 25 of the girders 22 and 23. As previously explained, any load transmitted through the connection provided by the ties 21 and the pipe lengths 27 is transmitted from the anchor bars 28 to the reinforcing bars 24 and 25 by the bond between them and the concrete of the girder.

The invention thus provides a simple and effective connection for securing precast members 50 firmly together in a building construction. No

special skill is required to make the connection and once made it remains permanently effective. The pipe lengths and anchor bars may easily be embedded in the concrete of the members by properly placing them in the mold in which the latter are made, along with the primary reinforcing bars 24 and 25.

Although I have illustrated and described a preferred embodiment of the invention, it will be recognized that changes in the construction disclosed may be made without departing from the spirit of the invention or the scope of the appended claims.

I claim:

1. A precast reinforced concrete unit comprising an elongated mass of concrete having embedded therein and bonded thereto a longitudinally extending reinforcing bar and also having embedded therein and bonded thereto a metal member having a bore therein disposed transversely to and adjacent an end of the longitudinally extending reinforcing bar, the metal member intersecting a surface of the concrete mass and being adapted to receive a connecting member, and an anchor bar also embedded in and bonded to the elongated mass of concrete, the anchor bar being relatively short with respect to the longitudinally extending reinforcing bar and being disposed in generally parallel side-by-side relation to the longitudinally extending reinforcing bar, the anchor bar being rigidly secured to the metal member and having a free end, whereby stress imparted to the unit through the metal member and the anchor bar rigidly secured thereto is transmitted to the longitudinally extending reinforcing bar through the concrete bonded to the anchor bar and the longitudinally extending reinforcing bar.

2. A precast reinforced concrete unit comprising an elongated mass of concrete having embedded therein and bonded thereto a longitudinally extending reinforcing bar and also having embedded therein and bonded thereto a metal member having a bore therein disposed trans-

versely to and adjacent an end of the longitudi-

nally extending reinforcing bar, the bore in said metal member being in communication with a surface of the concrete mass and being adapted to receive a connecting member, and an anchor bar also embedded in and bonded to the elongated mass of concrete, the anchor bar being relatively short with respect to the longitudinally extending reinforcing bar and being disposed in generally parallel side-by-side relation to the longitudinally extending reinforcing bar, the anchor bar being rigidly secured to the metal member and having a free end, whereby stress imparted to the unit through the metal member and the anchor bar rigidly secured thereto is transmitted to the longitudinally extending reinforcing bar through the concrete bonded to the anchor bar and the longitudinally extending reinforcing bar.

ALBERT HENDERSON.
